UNITED STATES PATENT OFFICE.

WALDOW F. MYERS, OF FOSTORIA, OHIO.

BOLT-LOCK.

1,087,041.

Specification of Letters Patent.

Patented Feb. 10, 1914.

Application filed April 19, 1913. Serial No. 762,397.

To all whom it may concern:

Be it known that I, WALDOW F. MYERS, a citizen of the United States, residing at Fostoria, in the county of Seneca and State of Ohio, have invented new and useful Improvements in Bolt-Locks, of which the following is a specification.

The present invention relates to improvements in bolt locks and resides in the construction, combination and arrangement of parts set forth in the following specification and falling within the scope of the appended claims.

The drawings illustrate a satisfactory reduction of my improvement to practice, and in said drawings: Figure 1 is a perspective view illustrating my improvement in connection with a rail chair employed in connecting two rail ends, Fig. 2 is a top plan view of the same, Fig. 3 is a transverse sectional view on the line 3—3 of Fig. 2, Fig. 4 is a similar sectional view on the line 4—4 of Fig. 2, Fig. 5 is a horizontal sectional view on the line 5—5 of Fig. 3, Fig. 6 is a detail perspective view illustrating the rails in position upon one member of the chair, preparatory to receiving the second member of the chair, Fig. 7 is a view of the improvement illustrating the bolt locking caps removed, Fig. 8 is a perspective view looking toward the underface of one of the bolt caps, and Fig. 9 is a longitudinal sectional view illustrating the slidable latch members provided upon the block and adapted to secure the block in position, Fig. 10 is an enlarged inverted perspective view of the block illustrated in Fig. 9, Fig. 11 is an enlarged sectional view showing the manner in which the sliding bolts are forced to withdraw in the recesses when the cap block is inserted over the head of the bolt.

In the drawings my improved nut lock has been shown in connection with a rail chair, the same being primarily adapted for use in connection with rail chairs, and in the following description, the same will be referred to in such connection. It is, however, to be understood that the improved nut lock is not to be thus restricted in its useful employment.

In the drawings, the rails are indicated by the characters R—R, while the ties upon which the rails rest are indicated by the characters T—T. The rails and ties are each of the ordinary construction, the base flanges of the rails, adjacent their ends, be-

ing, however, notched at their longitudinal edges, as indicated by the numeral 1.

The numeral 2 designates the chair in its entirety. The chair comprises a base 3 which is of a length corresponding to the distance between the ties T—T, and the said base may be secured to the ties if desired, in any desired manner. However, the ends of the base may merely frictionally contact with the opposite sides of the ties T, and the roadbed may be tamped beneath the base to raise the same flush with the upper faces of the ties. The base 3 is integrally formed upon one of its longitudinal edges with a vertically projecting portion 4 which is formed with an inwardly extending angular flange 5, the space between the said flange and the base being sufficient to receive the base flanges of the rails R—R upon one of the sides of said rails. Disposed between the angular flange and the base, and integrally connected therewith as well as to the inner face of the vertical portion 4 are lugs 6, these lugs being adapted to engage within the notches 1 in the flanges of the rails. The upper flat face of the base 3 to the opposite side thereof from its portions 4 and 5, is formed with a plurality of spaced threaded depressions or openings 7, two of which being shown in the drawings.

The numeral 8 designates the removable member or side for the chair. This member 8 embodies an angular upper portion 9 which terminates in a substantially vertical portion 10, the lower face of said portion 10 being horizontally straight and being adapted to rest upon the flat face of the base 3. The member 8 has its underface at its juncture with its angular and vertical portions formed with lugs 11, the said lugs being adapted to be received within the notches 1 upon this side of the rails R. The upper face of the member 8 is provided with spaced depressions forming pockets 12, and the lower wall 13 of each of the said pockets is provided with an aperture or opening 14 which is adapted, when the said member is arranged upon the base 3, to register with each of the threaded openings 7 in the base. Passing through the openings 14, and engaging with the threads of the openings 7 are headed bolts 15, the heads of which being adapted to rest upon the lower walls of the pockets 12 when the bolts are screwed entirely home. When the member 8 is thus connected to the

base 3 its vertical portion 10 has its inner face engaging with the longitudinal edges of the base flanges of the rails, while the angular portion 9 is forcibly brought into contact with the base flanges of said rails. It may here be stated that the angular portions 5 and 9 of the chair have their inner longitudinal walls vertically straight, and the said walls are adapted to tightly 10 press the opposite faces of the webs of the rails at the juncture of the said webs with the base flanges of the rails.

In order to effectively retain the bolts 15 against accidental removal or unscrewing, incident to the vibration to which the rails are subjected, I provide what I will term a cap block 16 for each of the pockets 12. These blocks are of a size and shape to be snugly received within the said pockets 20 and to frictionally engage with the walls of the pockets. The blocks may, and preferably do, have their inner edges at the lower portions thereof formed with extending tongues 17, the said tongues 25 preferably having their upper faces inclined or beveled from their juncture with the cap blocks to their outer edges, and the inner longitudinal walls provided by the pockets are formed with substantially V-shaped 30 grooves 18 which are adapted to receive the tongues 17. The cap block may be made of malleable material, and each of said blocks is provided upon its underface with a depression or channel 13, the walls of 35 which are inclined, so that the mouth of the opening 19 may be passed freely over the upper portion of the head of the bolt, and upon being forced downwardly to within the pocket will cause said walls to expand 40 to force the sides of the block into tight frictional engagement with the sides of the pocket 12. The outer edge of each of the blocks 17 is provided with a depression 20 which is inclined to the lower wall of said 45 block, the said depression providing means whereby a pinch-bar may be inserted between the block and the upper wall of the pocket to remove the block from the pocket. Other means may be employed for securing 50 the cap blocks within the pockets if desired, as for instance, and as illustrated in Fig. 9 of the drawings, the said block may be provided with transverse openings which enter the depression 19, and arranged with- 55 in said openings are sliding bolts 21 which have beveled inner ends 22, the said beveled ends being adapted to contact with the opposite faces of the bolt to slide the same to force their opposite ends into grooves 23 60 formed in the opposite side walls of the pocket.

From the above description, taken in connection with the accompanying drawings, the simplicity of the device as well as the 65 advantages thereof will, it is thought, be

perfectly apparent to those skilled in the art to which such inventions appertain without further detailed description.

Having thus described the invention, what is claimed as new is:

1. A member comprising a base provided with threaded openings, a member for the base, said member having its upper face formed with pockets, and the lower wall of the pockets having openings which are 70 adapted to register with the openings in the base, headed bolts passing through the openings and engaging with the threaded openings in the base, a cap member for each of the pockets, each of said caps being provided with a bolt head receiving depression which is adapted to engage with the head of the bolt to prevent the rotation of the bolt, and means for retaining the cap members within the pockets.

2. A member including a base having threaded openings, a second member adapted to be arranged over the base, said second member having its upper face at its outer edge formed with pockets, and the lower walls of the pockets being formed with openings which are adapted to register with the openings in the base, a headed member 90 passing through each of the openings and coöperating with the threaded openings in 95 the base, a cap member for each of the said pockets to close the same, each of said cap members having a bolt head receiving depression, the cap members being each formed with a tongue and one of the side 100 walls of each of the pockets being provided with a groove for the reception of the tongue.

3. The combination with a member including a base having threaded openings arranged adjacent one of its ends, a second member adapted to engage with the base and to overlie the portion thereof provided with the openings, said second member being formed with pockets corresponding in 105 number to the threaded openings of the base, and each of the said pockets being provided with an opening which is adapted to register with the corresponding threaded opening in the base, the inner walls of the 110 pockets being provided with grooves, headed bolts passing through the openings provided in the pockets and engaging with the threaded openings in the base, a cap for each of the pockets, said cap having its underface provided with a bolt head receiving depression, said cap being further provided upon its inner edge with tongues 115 which are adapted to be received within the grooves of the pocket when the caps are forced into the pockets and to have the walls of their depressions engage with the heads of the bolts, and means for retaining the caps within the pockets.

4. The combination with a member hav-

ing threaded openings, a second member adapted to be arranged upon the first member and to overlie the openings, the second member being provided with pockets which 5 register with the openings in the first member, the second member being provided with openings which enter the pockets, headed bolts passing through these openings and engaging the threaded openings in the first 10 mentioned member, the inner walls of the pockets being formed with grooves, the side walls of the pockets being also formed with depressions, a cap having a bolt head receiving opening for each of the pockets, said 15 cap having its inner edge provided with tongues which are adapted to engage with

the grooves provided by the inner walls of the pockets, said cap having transverse openings which enter their bolt head receiving openings, slideable latch members within 20 each of the said openings, said latch members having inner beveled edges, and adapted, when contacted by the heads of the bolts, to be forced through their openings into the grooves in the side walls of the pockets. 25

In testimony whereof I affix my signature in presence of two witnesses.

WALDOW F. MYERS.
